UNITED STATES PATENT OFFICE.

FORMAN F. FOWLER, OF WOLCOTT, NEW YORK, ASSIGNOR OF ONE-HALF TO
M. V. B. WALDORF, OF SAME PLACE.

SEAT-SPRING FOR WAGONS.

SPECIFICATION forming part of Letters Patent No. 334,425, dated January 19, 1886.

Application filed June 29, 1885. Serial No. 170,161. (No model.)

To all whom it may concern:

Be it known that I, FORMAN F. FOWLER, of Wolcott, in the county of Wayne and State of New York, have invented certain Improvements in Seat-Springs for Wagons, of which the following is a specification.

The aim of this invention is to provide a spring attachment which may be sold in the market, and readily adjusted by the purchaser to any lumber-wagon or other wagon having bolster with stakes or equivalent upright arms, to sustain a wagon-body, or a seat in the absence of the body; and to this end it consists, essentially, in a plate provided with a coiled or equivalent sustaining-spring, and with adjustable guides to engage the stake.

Referring to the drawings, Figure 1 represents a bottom plan view of a seat provided with my attachments. Fig. 2 is a vertical longitudinal section of the same. Fig. 3 is a cross-section on the line *yy*. Fig. 4 is a top plan view showing the base-plate with adjustable devices for connection to the bolster.

In the drawings, A represents a plate, which may be of any appropriate form adapted to be screwed or otherwise secured to the under side of a wagon seat or board.

B is a spiral spring, secured at the upper end to the top plate and at the foot to a base-plate, C, designed to be secured to the bolster. The top plate is provided with a notch or opening to admit the stake by which it is guided, and with three guide-plates, *a*, slotted and secured in place by bolts, so that they may be adjusted to suit the size of the stake embraced between them. The inner ends of the plates are preferably provided, as shown, with rollers *d*, to act against the stake and thus reduce the wear and friction. The base-

plate is provided, as shown, with arms *e*, secured in place by bolts, so that when the plate is seated in position on the bolster the arms or clamps may be adjusted to embrace its sides and hold the plate in place, as shown.

In making use of the device it is secured one to each end of the seat or a cross-board to sustain the wagon-body, and the whole placed in position on the wagon, the stakes being pointed to pass between the rolls and the base-plate secured to the bolster, as shown.

Having thus described my invention, what I claim is—

1. The spring attachment for wagons, consisting of the spring, the top plate secured thereto, the guides adjustably secured to the plate, and the base-plate provided with adjustable devices for attachment to the bolster.

2. In a spring attachment for use on existing wagons, a spring, in combination with a top plate secured thereto, and the horizontally-adjustable guide-rolls secured to the plate, whereby the guides may be adjusted to standards of different sizes.

3. In combination with a seat-sustaining spring, a base-plate adjusted to extend across the top of the bolster and provided with arms to clasp the two sides of the same, and a top plate recessed to admit the standard, said members constituting, jointly, a spring attachment applicable to wagons of ordinary construction.

In testimony whereof I have hereunto set my hand, this 16th day of May, 1885, in the presence of two attesting witnesses.

FORMAN F. FOWLER.
